FUEL INJECTION DEVICE FOR INTERNAL
COMBUSTION ENGINES

Heracio Alfaro, Boston, Mass.

Application October 16, 1935, Serial No. 45,289

2 Claims. (Cl. 123—32)

The present invention appertains to the injection of fuel into the cylinders of internal combustion engines, and is particularly adaptable to cylinders having two pistons per cylinder operating on the two-stroke cycle principle with spark ignition.

My invention contemplates means whereby the fuel can be thoroughly mixed with the air charge in a cylinder without excessive dilution of the fuel with the lubricating oil on the interior wall of said cylinder.

The main objects of the invention are to obtain a very complete atomization of the fuel and a very thorough mixture of the fuel particles with the air, to effect economy in fuel consumption, and to make the firing of the fuel charges certain and dependable, and to obtain these results without detrimental effect on lubrication.

Reference should be had to the accompanying drawings forming a part of this specification, in which:

Figure 1 is a sectional view showing a fuel injection device embodying the invention;

Fig. 2 is a sectional view showing a fuel injection device of somewhat different construction also embodying the invention;

Fig. 3 is a sectional detail view showing the outlet of the injection nozzle in open position;

Fig. 4 is a sectional detail view showing the spray forming tip of the nozzle in side elevation;

Fig. 5 is a sectional detail view showing a deflector which may be used with the nozzle shown in Figs. 2, 3, and 4;

Fig. 6 is a diagrammatic view showing a complete cylinder, the injection nozzle, ignition devices and the streams or jets which may be discharged from the injection nozzle into the space between the pistons by a suitable arrangement of the outlet openings of the nozzle shown in Fig. 1;

Fig. 7 is a view similar to Fig. 6 showing the fuel streams or jets obtained by a different arrangement of outlet openings;

Fig. 8 shows fuel streams or jets which may be obtained by another arrangement of outlet openings;

Fig. 9 shows the fuel streams or jets obtained by two oppositely disposed oblique discharge openings;

Fig. 10 is a view showing the fuel streams or jets obtained by the nozzle and deflector shown in Fig. 5;

Fig. 11 is a view showing oppositely disposed injection nozzles;

Fig. 12 is a sectional view showing a modification of the invention in which the fuel injection nozzle is mounted in an air inlet port.

Heretofore it has been difficult to combine proper atomization of the fuel with low penetration and efficient mixing when the size of the cylinder is relatively small and the compression at the time of the injection is low. Moreover injection nozzles heretofore used have been expensive and bulky, or have required the installation of leak-off lines. The present invention avoids these difficulties.

In Figs. 1 to 5 the construction of the fuel injection nozzles embodying the invention are shown in detail, the arrangement of the nozzle 1 with respect to the cylinder and pistons therein and with respect to the air intake and ignition devices being shown in diagrammatic views 6 to 11 inclusive.

Referring to Fig. 1 of the drawings, the injection nozzle indicated generally by the numeral 1 is mounted in an apertured threaded boss 2 of a cylinder 3 and has a body portion 4 provided with an axial bore 5 which terminates near the inner end of the body portion. The body portion 1 has a rounded tip 6 of reduced diameter which is provided with divergent openings 7 which provide outlets from the chamber formed by the bore 5 and which may be arranged in various ways to so direct streams of fuel into the cylinder as to effectively disperse the fuel in the air within the cylinder as will be hereinafter more fully explained.

The body portion 4 of the nozzle has a reduced cylindrical inner end portion 8 which fits within a sleeve 9 which fits within the aperture of the boss 2 and has a flange 10 adapted to seat upon the outer edge of the boss 2. The body portion 4 of the nozzle has a flange 11 which seats upon the flange 10 of the sleeve 9 and is clamped to the cylinder by a sleeve nut 12 which screws upon the threaded boss 2. The sleeve 9 is preferably made of copper or other metal of high heat conductivity.

A fuel inlet nipple 13 provides means for admitting fluid fuel into the chamber formed by the bore 5. At the upper end of the body 4 the bore 5 is closed by an elastic wall 14 clamped upon the upper end of the body 4 by means of a screw cap 15. The elastic wall or diaphragm 14 is provided with circular corrugations 16 and is deformable by internal fluid pressure, the upper end of the body 4 being countersunk around the upper end of the bore 5 to provide an enlargement 17 in the pressure chamber beneath 55

the elastic wall 14. A valve stem 18 is rigidly attached to the center of wall 14 and extends through the bore to adjacent the outlet and where it is provided with a conical faced valve member 19 which bears against a valve seat to cut off flow of fluid to the discharge tip 6. The valve member 19 is normally held firmly seated by the elastic wall 14 to cut off flow of fluid to the interior of the cylinder. Near the end of the piston stroke fluid under pressure is delivered to the nozzle 1 by the usual mechanism timed with respect to the piston movement. This fuel entering the bore 5 of the nozzle under high pressure acts upon the elastic wall 14 bending the wall outwardly and retracting the valve member 19 from its seat to permit fuel to flow from the nozzle chamber into the tip 6 and through the openings 7 into the cylinder. The valve member 19 preferably has a sliding fit in the bore 5 and is provided with grooves 20 to permit flow past the valve when the valve is shifted away from its seat. To prevent damage to the elastic wall 14 due to excessive deformation by internal pressure, means is provided to limit the deflection of the wall 14. The wall of the cap 15 is closely adjacent the outer face of the elastic wall 14 and will permit the wall 14 to have only a very slight outward movement. In order to permit free escape of air from the space between the cap 15 and elastic wall 14 the cap is provided with openings 21.

In Figs. 2, 3, and 4 a modified form of injection nozzle is shown. This nozzle indicated generally by the numeral 1a has a body portion 22 provided with a threaded end adapted to screw into a threaded boss 23 in the cylinder wall. The body portion 22 is bored to receive a cylindrical fuel conducting member 24 which has a reduced tapered elastic walled tip 25 which extends through a restricted opening at the inner end of the body 22. The opening at the inner end of the body 22 is provided with a tapered seat 26 against which the tapered tip 25 bears and against which the tapered tip is pressed by means of a ring nut 27 which screws upon the threaded outer end of the body 21 and bears upon the outer face of a flange 28 on the member 24. The member 24 has an axial passage 29 for fluid fuel. The tip 25 is formed of two elastic wall-forming members having flat faces which abut in an axial plane and which are held firmly in contact by pressure against the tapered seat 26. The abutting faces are provided with grooves 30 which form a continuation of the passage 29 and have recesses 31 near their ends which provide an enlargement of the pressure chamber. The opening in the body 21 is enlarged between the seat 26 and the inner end of the body so that the ends 32 of the elastic walls of the tip are free to bend laterally when acted upon by the pressure of fluid in the chamber formed by the recesses 31 to separate the contacting walls at the end of the discharge tip and thus provide a narrow slit around the end and inwardly along the sides of the tip 25 through which a flat stream of fluid fuel may flow into the interior of the cylinder. The body 21 is provided with stop shoulders 33 closely adjacent the opposite sides of the outer end of the tip 25 to limit the amount of bending and prevent stressing of the material of the tip beyond its elastic limit. The elastic walls forming tip 25 are preferably composed of metal and may be formed integrally with the member 24. However, the halves of the tip 25 are preferably separate parts with accurately

formed faces which insure fluid-tight contact. The contacting faces of the tip halves and the contacting faces of the ends of the tip halves and the member 24 are preferably lapped.

If desired, a deflector 34 may be mounted upon the inner end of the nozzle body 22 immediately adjacent the end of the tip 25 to deflect fuel discharging from the end of the tip laterally in the direction of the flat streams issuing from the sides of the tip.

Figs. 6 to 11 show diagrammatically an entire cylinder 3, with the injection nozzle mounted midway between the ends of the cylinder, pistons 35 positioned at or near the outer ends of their strokes and spark plugs 36 positioned centrally of the cylinder and in circumferential alignment with the injection nozzle. Air inlet ports 37 are positioned near one end of the cylinder so as to be uncovered by the piston at that end as the piston nears the outer end of its stroke, and exhaust ports 38 are positioned near the opposite end of the cylinder, the injection of fuel and entry of air into the cylinder being timed to occur at or near the time when the pistons are in their outermost positions.

To obtain best results, the location of the nozzle and the direction of the sprays of fuel are important. When used in combination with a double opposed piston cylinder, I have found it advantageous to place the nozzle of the type shown in Fig. 1 in the center of the cylinder which corresponds to the space where the combustion of the fuel actually takes place.

If the operation of the engine is on the fuel injection spark ignition principle, I have found it advantageous to inject the fuel following the longest possible path and furnishing as much diffusion as possible with the air in the cylinder. This is better achieved when the two pistons are at or near the outer end of their stroke.

Figs. 6, 7, 8, 9, 10, and 11 show various forms of sprays on this same principle, the main object being to inject from a point of the cylinder along the longest path and providing the greatest possible contact between the spray boundary and the air.

Fig. 6 for instance shows in perspective an arrangement that provides four jets or streams 7a directed obliquely across the cylinder towards the faces of pistons 35, the nozzle outlet in this instance being provided with pairs of openings 7 at opposite sides thereof, each pair being disposed in a plane extending obliquely across the cylinder axis and intersecting the face of a piston.

Fig. 7 shows four streams or jets 7b all disposed in a single plane with a pair of jets directed toward the face of each piston. In this instance two of the jets 7b are directed toward the centers of the faces of the opposed pistons and the other two jets are directed across the cylinder at a greater angle to the cylinder axis.

Fig. 8 shows six jets 7c disposed in three planes, an arrangement which will provide better dispersion in large cylinders.

Fig. 9 shows two jets 7d such as provided by two openings 7 directed obliquely toward opposite ends of the cylinder.

Fig. 10 shows the fuel streams produced by the nozzle and deflector shown in Fig. 5. The flat fuel streams or jets are indicated by the numeral 39.

In some instances it may be desirable to provide a plurality of injection nozzles. Fig. 11 shows two nozzles 1 arranged diametrically oppo-

site each other in the central portion of the cylinder.

Fig. 12 shows a modified construction in which a fuel injection nozzle indicated by the numeral 5 $1b$ may be mounted in an air inlet port 38 and provided with an outlet adapted to direct a jet indicated at $39a$ obliquely toward the opposite end of the cylinder at a relatively small angle to the axis of the cylinder.

10 It can be seen that I have provided advantageous means to inject the fuel in the cylinders of internal combustion engines of the type having two opposed pistons per cylinder. By providing an elastic walled chamber deformable by fluid 15 pressure and opening the discharge outlet when so deformed, leakage and the resulting need of leak-off pipes is avoided. By providing limiting stops for the elastic members, fatigue of the elastic elements is avoided. By directing the sprays 20 along the longest paths in the cylinder and by properly distributing the sprays in the proper directions, a more perfect mixture of the fuel with the air is obtained, resulting in fuel economy and avoiding or reducing dilution of the oil film 25 on the cylinder wall.

Furthermore, it is to be understood that the particular form of apparatus shown and described, and the particular procedure set forth, are presented for purposes of explanation and

illustration and that various modifications of said apparatus and procedure can be made without departing from my invention as defined in the appended claims.

What I claim is:

1. In an internal combustion engine having two opposed pistons per cylinder, means for injecting fuel into said cylinder at times when the pistons are near the outer end of their stroke, said injecting means including a nozzle in the 10 wall of the cylinder at one side thereof substantially midway between its ends, said nozzle being provided with means for directing divergent streams of fuel across the cylinder from the nozzle and toward the heads of the two pistons 15 while the pistons are near the outer ends of their stroke.

2. In an internal combustion engine having two opposed pistons per cylinder, means placed in the wall of the cylinder at one side thereof substantially midway between its ends for injecting fuel into said cylinder at times when the pistons are near the outer end of their stroke, and means for directing the fuel from said injecting means in divergent planes across the cylinder from said injecting means and toward the heads of the two pistons while the pistons are 20 near the outer ends of their stroke.

HERACLIO ALFARO.
